UNITED STATES PATENT OFFICE.

CHARLES A. LANTZ, OF WELSH, LOUISIANA.

WELL-TUBING.

No. 798,910.

Specification of Letters Patent.

Patented Sept. 5, 1905.

Application filed February 25, 1905. Serial No. 247,376.

To all whom it may concern:

Be it known that I, CHARLES A. LANTZ, a citizen of the United States, residing at Welsh, in the parish of Calcasieu and State 5 of Louisiana, have invented new and useful Improvements in Well-Tubing, of which the following is a specification.

The invention relates generally to improvements in well-tubing for use in drive-wells, 10 bored wells, or other wells drilled or bored by whatever process, and particularly to a strainer or screen for the lower or point end of the tubing used in water-wells, oil-wells, gas-wells, or any other wells where screens 15 are used or necessary.

The main object of the invention is the provision of a strainer particularly designed to permit free access of water, oil, or sand to the tubing and constructed to avoid the clogging 20 usually incident to strainners of this character.

The invention is illustrated in the accompanying drawings, wherein—

Figure 1 is a view in elevation, partly in section, of my improved strainer. Fig. 2 is 25 an enlarged transverse section of the same. Fig. 3 is a broken elevation of the spacing-strip for use with the strainer-casing. Fig. 4 is a view in elevation of a modified form of wrapping for the strainer-casing. Fig. 5 is a 30 similar view of another form of wrapping.

Referring to the drawings, 1 represents the strainer-casing, preferably perforated, as at 2, and designed to be connected as the lower 35 section of the usual well-tubing. The lower end of the casing is provided with the usual threaded extension 3 to receive the ordinary drive-point.

4 represents what I term "spacing-strips," 40 comprising, preferably, elongated sections having depending teeth or ribs 5. These strips are secured on the outer side of the strainer-casing with their ribs 5 in contact with the peripheral surface of said casing. The strips are preferably arranged intermediate the longitudinal rows of perforations in the casing 1, the spaces between the ribs 5 and between the strips 4 serving to permit free access of the material into the casing. As a medium for securing the strips in place and at the same 45 time providing openings through which the desired material may find its way into the casing I provide a wrapping 6, preferably of wire, designed to be wound about the casing in close contact with the outer surface of the 50 strip, the adjacent coils of the wire wrapping being in close contact. Practice has demon-

strated, however, that provision for the entrance of the material other than the openings normally between coils of plain wire so wound must be made, and this I provide by 60 using in the preferred form a flat wire 7, which is twisted upon itself, as shown, previous to being wound about the strip. This construction provides innumerable interstices or openings between the adjacent coils of the 65 wire 7, through which the material may find its way into the casing. The flat wire so twisted is particularly adapted for those wells delivering water; but for oil or sand wells I have found that the efficiency is 70 materially increased by constructing the wrapping of a wire having a shape other than flat. For instance, for the wrapping of a casing designed to serve as a screen in oil-wells the wire in its initial shape should be 75 square, as at 8, Fig. 4, and twisted longitudinally upon itself to provide practically the form shown in Fig. 4. This structure provides a larger number of openings between the adjacent coils of the wrapping and is 80 particularly effective for oil-wells.

For use in sand-wells the wire composing the wrapping is preferably hexagonal prior to its twisting, as shown in Fig. 5, as at 9. This form is particularly serviceable in excluding quicksand in oil or water wells, whereby to prevent the wells from choking up. 85

In the use of the invention the openings between the adjacent coils of the wrapping provide an entrance for the water, oil, or sand 90 into the well-casing, and this entrance or passage is further insured by the spacing of the strips 4 and the openings intermediate the ribs of each strip.

I am aware that it has been heretofore proposed to wrap the strainer of a well-tubing with wire; but the disadvantage of the plain wrap-wire is that the openings between the coils have in practice become clogged or stopped up, interfering materially with the 100 circulation through the strainer. By my invention this clogging is entirely obviated, as will be evident, and a full free circulation through the strainer maintained in all conditions of the well. 105

I do not desire to limit myself to the particular sectional formation of the wrapping-wires described, as other and varying forms may be readily used, it being understood that the gist of my invention resides in a perforated 110 well-casing carrying on the outer side thereof a series of longitudinally-arranged strips

having projecting ribs in contact with the well-casing, which strips and casing are enveloped in a wrapping of wire of a sectional shape other than round and twisted to provide when in place a number of openings between the adjacent coils.

Having thus described the invention, what is claimed as new is—

1. A well-tube strainer comprising a perforated casing, a series of spacing-strips on the outer side thereof, means for supporting said strips spaced from the surface of the casing, and a twisted-wire wrapping formed in close coils about said strips.
- 15 2. A well-tube strainer comprising a perforated casing, a series of strips spaced on the outer side thereof, means for supporting said strips spaced from the surface of the casing, and a wire wrapping formed in close coils about said strips, said wire being of angular shape in cross-section and twisted longitudinally.
- 20

3. A well-tube strainer comprising a perforated casing, a series of strips longitudinally arranged and spaced apart on the outer surface of said casing, said strips having projecting ribs arranged in contact with the surface of the casing, and a wire wrapping formed in close coils about said strips.

4. A well-tube strainer comprising a perforated casing, a series of strips longitudinally arranged and spaced apart on the outer surface of said casing, said strips having projecting ribs arranged in contact with the surface of the casing, and a wire wrapping formed in close coils about said strips, said wire being angular in cross-section and twisted longitudinally.

In testimony whereof I affix my signature in presence of two witnesses.

CHARLES A. LANTZ.
